UNITED STATES PATENT OFFICE.

MORRIS N. CASTLEMAN, OF ROCKFORD, ILLINOIS, ASSIGNOR TO HIMSELF, CHARLES R. BISHOP, JOHN SPAFFORD, AND ROBINSON P. SEARL, ALL OF SAME PLACE.

CHURN-COVER.

SPECIFICATION forming part of Letters Patent No. 361,208, dated April 12, 1887.

Application filed December 27, 1886. Serial No. 222,655. (No model.)

To all whom it may concern:

Be it known that I, MORRIS N. CASTLEMAN, a citizen of the United States, residing in the city of Rockford, in the county of Winnebago and State of Illinois, have invented a new and useful Improvement in Churns, of which the following is a specification.

This invention relates to heads or lids of churns or other vessels, made removable. Its object is to provide a removable head for churns or vessels to produce a tight joint, and having a secure fastening to fix it in place in a manner to be readily applied and readily removed.

15 To this end I have designed and constructed the head represented in the accompanying drawings, which will be hereinafter more fully described.

In the accompanying drawings, Figure 1 is 20 an isometrical representation of a removable head for vessels embodying my invention. Fig. 2 is an isometrical under face view of my improved removable head. Fig. 3 is an isometrical outer face representation of the annular-ring-head portion of my improved removable head. Fig. 4 is an under face representation of the removable disk portion of the removable head. Fig. 5 is a central sectional representation on the dotted line *a* on 25 Fig. 1; and Fig. 6 is an enlarged section of the grooved edge portion of the disk-head on the dotted line *b*, Fig. 4.

In the figures, 1 represents a metallic annular-ring head having its peripheral edge 35 formed to enter the croze or groove as usually formed in the inner face of the vessel near its end. The inner edge of the annular-ring head on its outer face is formed with an uprising bead-formed edge, 2, for a purpose to appear 40 hereinafter. The annular-ring head is also formed with holders 3, rising from its outer face at any proper intervals. The holders 3 rising from the outer face of the annular-ring head are formed on their inner face with a recess, 4, having the inner face of its outer portion inclined to the plane of the annular-ring head, for a purpose to appear hereinafter.

A metallic disk-head, 5, preferably produced from plate material, is formed with an 45 annular groove, 6, on its inner-face peripheral

edge, and its central portion within the annular groove is produced in crowning form, as in the figures. A cork or other suitable elastic packing, 7, is placed within the annular groove 6 in the disk-head, and is designed to 55 engage the bead on the outer-face inner edge of the annular-ring head. A metallic spider, 8, of substantially the same diameter as the disk-head, is pivotally connected at its center with the center of the disk-head to turn independently.

The outer annular rim, 9, of the spider engages the outer surface of the grooved portion of the disk-head, and its peripheral edge is provided with inclined or wedge-formed projections 10, to enter the recesses 4, formed in the inner face of the holders 3 rising from the annular-ring head.

Handles 11, rising from the peripheral outer side face of the spider, extend outward and 65 furnish the means for handling the removable head and to rotate it on its pivotal connection with the disk-head.

My removable lid is composed, essentially, of three parts, to wit: an annular-ring head to 75 be fixed in the vessel, a removable disk-head to engage the annular ring, and a spider in connection with the annular-ring head to fix the disk-head in place on the annular-ring head in a removable manner.

It is evident that slight changes might be resorted to in the form and arrangement of the several parts described without departing from the spirit and scope of my invention, and hence I do not wish to limit myself strictly to 85 the construction herein set forth.

In the foregoing I have employed holders of rather small dimensions rising from the annular-ring head, grooved on their inner face to receive the inclined or wedge-formed projections of the spider; but it is evident that a reversal of these parts, in which the long incline could be formed on the annular-ring head and a short projection on the spider to engage the incline on the ring-head, would be 95 within the scope of my invention.

In the manufacture of my improved disk-head from plate material, I prefer to produce it from a single piece, in which instance the annular groove 6, to secure the packing, and also 100

its crowning form, are produced by striking up, stamping, or pressing. It may, however, be produced in parts, as shown in Fig. 6, in which the central crowning portion, the vertical annular side walls, 12, and the annular cap 13 are formed in separate parts, seamed, grooved, soldered, or otherwise joined at their several meeting points to form the annular groove 6 to receive the packing.

10 I claim as my invention—

15 1. In combination, an annular metallic ring adapted to be seated within the end of a barrel-like receptacle and provided with upwardly-extending holders and with an upwardly-extending annular bead around its inner edge, a metallic disk-cover having a crowning center, and an annular groove containing packing adapted to engage the said annular bead,

and a spider-clamp pivotally secured to the center of the cover and having cams adapted 20 to engage the holders, and a rim adapted to engage the cover over the packing, substantially as set forth.

2. In combination, the ring-head adapted to be seated within the head of the receptacle 25 and provided with a cover-receiving flange and upwardly-extending holders, the metallic disk-cover, with its crown-center and annular packing, and the spider-clamp pivotally secured to the cover at its center and provided with the operating-handle, substantially as set forth.

30 MORRIS N. CASTLEMAN.
